UNITED STATES PATENT OFFICE.

ORRELL ASHTON, OF LAWRENCE, MASSACHUSETTS, ASSIGNOR TO UNITED SHOE MACHINERY COMPANY, OF PATERSON, NEW JERSEY, A CORPORATION OF NEW JERSEY.

MACHINE FOR USE IN THE MANUFACTURE OF BOOTS AND SHOES.

1,030,762.

Specification of Letters Patent. Patented June 25, 1912.

Application filed March 30, 1908. Serial No. 424,225.

To all whom it may concern:

Be it known that I, ORRELL ASHTON, a citizen of the United States, residing at Lawrence, in the county of Essex and Commonwealth of Massachusetts, have invented 5 certain Improvements in Machines for Use in the Manufacture of Boots and Shoes, of which the following description, in connection with the accompanying drawings, 10 is a specification, like reference characters on the drawings indicating like parts in the several figures.

This invention relates to machines which are used in the manufacture of shoes and 15 particularly welt shoes, and is herein shown as embodied in a machine that is equipped with means for removing surplus material from the shoe by trimming off the projecting edges of the vamp and lining after the 20 shoe has been lasted, and before the inseam sewing operation.

An object of the present invention is to provide a machine by which the shoe blocking operation may be performed while another 25 operation, such for example, as the vamp trimming operation, is being carried on. This blocking operation has for its purpose to shape the shoe, particularly the side face of the shoe at and adjacent to the 30 edge of the shoe bottom.

An important feature of this invention consists in mechanism for blocking a lasted shoe while the shoe is being subjected to another operation so that no loss of time is 35 required for the blocking operation. More particularly stated, this feature of the invention consists in the combination with a blocking or shaping tool and a tool for performing a different operation on a shoe, of 40 connected mechanism for actuating the shaping tool and said other tool. As shown, the blocking tool is a reciprocating beater arranged below a vamp trimming knife and adapted to strike the side of the shoe while 45 the latter is in operative relation to the knife. The knife and beater are preferably arranged to operate in such time relation that the beater strikes the shoe while the latter is held by the cutters between the advances or feeding movements of the shoe. 50

Another feature of the invention consists in the combination with the blocking tool

and a second tool for operating on a shoe at the same time, of means under control of the workman for controlling the operation 55 of the blocking tool independently of that of the other tool. I have herein shown the machine as equipped with means whereby the workman can render the blocking tool operative or inoperative at any time and 60 can vary the force of the blows delivered by the blocking tool.

The machine is provided with means for guiding the shoe and the guiding means co-operates with the blocking tool to position 65 the shoe for the action of that tool. These guiding means include a device to engage the bottom of a welt shoe, and, by contacting with the face of the innersole and with the inner side of the lip or rib of the inner- 70 sole, to position the shoe both vertically and horizontally. The engagement of the guiding device with the innersole and particularly its lateral engagement with the lip or rib assists in sustaining the shoe 75 against the impact of the blocking tool. The guiding device is formed to permit the shoe to be tipped for varying the angle at which it is presented to receive the blows of the tool and it is also preferably driven 80 in the direction of the feed of the shoe and assists in advancing the shoe between successive operations of the tools.

A further feature of the invention consists in the combination with a blocking tool of a 85 tool arranged for movement over the last bottom from the edge of the last inwardly preferably to and against the portion of the upper that stands up adjacent to the lip or shoulder of the innersole. This tool not 90 only co-operates with the blocking tool to shape the edge of the shoe, but may force the upper snugly into the angle of union between the lip and the feather edge of the innersole to facilitate the formation of a 95 tight inseam. The end face of this tool may advantageously be formed to press downwardly and inwardly into said angle the wire or other binder by which the uppers of 100 welt shoes are usually held in lasted position while awaiting the inseam sewing operation. The guiding and feeding device may, by its engagement with the inner side of the lip, form an abutment opposed to the tool which

engages the upper at the outer side of the lip and coöperating therewith in creasing the upper into the angle.

These and other features of the invention, 5 including certain details of construction and combinations of parts, will be more fully set forth in the following description and then pointed out in the claims.

Figure 1 is a side elevation of a machine 10 embodying this invention; Fig. 2 is a plan view; Fig. 3 shows a modified arrangement of the blocking tool with relation to the trimming knife and also a tool adapted to be projected over the shoe bottom in coöperation with the blocking tool; Fig. 4 shows another view of the same.

The frame of the machine supports a driving shaft 2 having an eccentric embraced by a strap 4, as shown in dotted lines in Fig. 1. 20 This strap is connected to a reciprocating bar 6 that carries a knife 8 adjustably secured in position thereon by the bolt 10. The knife 8 coöperates with the fixed knife 12 suspended by a bracket 14 from the overhanging arm 15 of the frame and also supported by the shaft 16, which passes through it and is provided below the knife 12 with the feed roll 18. The shaft 16 is driven by a worm gear 20, meshing with a similar gear 30 on the shaft 22 which is driven by a belt 24 from a pulley on the shaft 2. The feed roll is provided on its periphery with ribs, as at 25, which tend to lift the vamp or lining with which they contact into position to be 30 acted upon by the cutters. The ribbed roll also tends to feed the shoe in the direction in which the operation is progressing. The shaft 2 is also provided with a cam 30 having in its side a groove 32, which at its inner edge is concentric with the shaft and at its outer edge is concentric through a portion of its length, forming at 34 a drop leading to a concentric portion 36. Standing in this groove is roll 38 on a reciprocatory bar 40 that carries at its front end a blocking tool 42. Projecting laterally from the bar 40 through a slot in the frame is a stud 44 embraced by the slotted upright arm of an angle lever 45. This lever, which is pivoted at 50 46, has an opening through which extends the treadle rod 48 connected to the treadle 50. A spring 52 is interposed between the head of the rod and the upper face of the horizontal arm of the angle lever. A light spring 54 connects the rear side of the angle lever with the frame and holds this lever rocked backwardly with the roll 38 normally against the concentric inner wall of the cam groove. When the roll is in this position the 55 blocking hammer remains at rest while the trimming knife 8 is reciprocated. By depressing the treadle 50 the roll 38 is forced against the outer wall of the groove and as the high point 34 passes the roll the blocking 60 hammer is actuated toward the shoe with a

force dependent upon the extent to which the spring 52 has been compressed. By depressing the treadle and compressing the spring 52 more or less the strength of the blows of the hammer can be varied during 70 the trimming operation and entirely independent of that operation.

In the use of the machine the workman presents the shoe in the position shown in Fig. 1 with the face of the innersole against 75 the lower end of the feed roll 18 and preferably with the inner face of the lip 55 against the periphery of the roll. By the reciprocation of the knife 8 the projecting edges of the vamp and lining are trimmed as shown. 80 The treadle 50 may be depressed to start the blocking hammer either when the shoe is first inserted so that the blocking operation will begin at the point where the trimming begins or the treadle may be depressed later 85 in the trimming operation to cause the blocking operation to begin at any desired point. The pressure on the treadle may be varied to cause more or less severe beating of the shoe to be effected and the strength of 90 the blows may be increased or diminished according to the requirements of each particular portion of the shoe. While the feed roll has a tendency to advance the work in the direction in which the operation is progressing the workman holding the shoe in his hands controls the rate at which the shoe 95 is advanced and can hold the shoe stationary at any particular point while the blocking hammer thoroughly beats the upper on the 100 side of the shoe at any places that require special treatment. In this way wrinkles or inequalities in the side of the shoe can be quickly beaten out.

It is to be observed that the blocking hammer is formed on its outer acting face to engage the side of the shoe at and adjacent to its edge and preferably the hammer extends slightly above the edge of the shoe and also extends downwardly along the side of the 110 shoe for some distance. The roll 18 is formed as a truncated cone having its smaller end in position to contact with the insole and constitutes a rest about which the shoe may be tipped to vary the presentation 115 of the shoe according to the contour of the particular portion of the shoe being blocked.

In Figs. 1 and 2 the blocking hammer is mounted on a separate slide from that which carries the trimming knife 8 and is independently actuated.

In the modified construction shown in Figs. 3 and 4 the blocking tool, indicated at 60, is mounted upon the knife bar 6. In this construction the bolt 10 secures upon the bar 125 6 a carrier 62 in which the tool 60 is yieldingly mounted and arranged to slide forwardly and backwardly. The tool is held in its foremost position by a spring 64 pressing against a stud 65 projecting upwardly 130

from the blocking tool 60 through a slot in the carrier 62. In this construction it will be understood the blocking tool is operative at all times when the trimmer is in use. A 5 feature of this construction is that the carrier 62 is provided with an end portion 66 adapted to project outwardly beyond the blocking tool 60 when the latter is in its backwardly pressed position and to overlie 10 the marginal portion of the shoe bottom at this time. The reciprocating member 66 which thus forms a third tool in the construction shown preferably projects over the shoe bottom far enough to press the vamp 15 against the outer face of the lip 55 of the innersole. The lip abuts on its opposite side against the feed roll 18 and the member 66 therefore serves to crease the upper material into the angle between the feather edge of 20 the innersole and the outer face of the lip and to beat the upper against said outer face of the lip, while the roll 18 forms an abutment for the inner face of the lip. When 25 the vamp is bound in position by a wire 68, as is usual, the member 66, which for the purpose of identification will be called the creasing tool, serves to force or beat the wire into holding position. To this end it is formed with an inclined face at 69 to crowd 30 the binder downwardly and inwardly into position to hold the upper in the angle between the lip and feather edge of the inner-sole. By forcing the upper snugly into the angle a tighter inseam can be formed in the 35 subsequent sewing operation. Obviously the blocking tool 60 with the creasing tool 66 arranged relatively thereto, as just described, may be mounted on a slide separate from the knife, as, for example, in place 40 of the blocking tool 42, or these blocking and creasing tools may be used with a tool other than a vamp trimming knife, or may be used independently of any other tool.

The machine may be equipped with an 45 upper bending device, shown at 70. In Figs. 1 and 2 the vamp bending device is adjusted, by its slot connection with the clamping bolt 10, into a retracted position while in Figs. 3 and 4 it occupies its operative position. As shown in these latter figures, the 50 bending device is adapted to turn the upper from an outwardly flaring position into an upright position to facilitate the trimming operation.

55 The novel features of the above described construction shown in Figs. 3 and 4 of the drawings are not claimed herein, forming the subject matter of a co-pending divisional application, Ser. No. 657,135, filed Oct. 27, 60 1911.

Having explained this invention and described mechanism embodying the same in the best form now known to me, I claim as new and desire to secure by Letters Patent 65 of the United States:—

1. A machine of the class described, having in combination means for removing surplus material from the projecting edges of the vamp of a lasted shoe, a blocking tool, and connected mechanism for actuating the 70 tool and said means.

2. A machine of the class described, having in combination means for removing surplus material from a lasted shoe, a tool for beating the side of the shoe to block it while 75 it is being trimmed, means for actuating said means, connected mechanism for actuating the blocking tool, and means under control of the workman for controlling the force of the blows of the blocking tool. 80

3. A machine of the class described, having in combination vamp trimming knives arranged to trim the projecting edges of the vamp of a lasted shoe, a blocking tool, connected mechanism for actuating the tool 85 and the knives, and means for rendering the blocking tool operative or inoperative while the knives continue in operation.

4. A machine of the class described, having in combination means for removing surplus material from a lasted shoe, a blocking tool, a spring for actuating the tool toward the shoe, a cam for reversely actuating the tool and putting the spring under compression, means for normally maintaining the 90 tool out of operative relation to the cam, and means under control of the operator for causing the tool to be operated by the cam. 95

5. A machine of the class described, having in combination vamp trimming knives 100 arranged to trim the projecting edges of the vamp of a lasted shoe, a blocking tool, a cam, a spring, and means under control of the operator for putting the tool into operative relation to the cam and for varying the 105 tension of the spring to control the force with which the tool is actuated.

6. A machine of the class described, having means for operating on a shoe, actuating mechanism therefor, a blocking tool to 110 shape the shoe upper, a cam, a spring, and devices under control of the operator for putting the tool into operative relation to the cam and for varying the tension of the spring to control the force with which the tool is actuated. 115

7. A machine of the class described, having a blocking tool to beat the side of a shoe and means for positioning the shoe relatively thereto comprising a roll constructed 120 and arranged to engage the bottom of a welt shoe at the inner side of the lip.

8. A machine of the class described, having a reciprocating blocking tool to beat the side of a lasted shoe, means for positioning the shoe relatively thereto comprising a roll, and means for actuating the roll in the direction to feed the shoe past the blocking tool. 125

9. A machine of the class described, hav- 130

ing a tool for working on the side of a shoe and means for positioning the shoe relatively thereto comprising a roll constructed and arranged to engage the inner side of the lip of the inner sole of a welt shoe and means for actuating the roll in the direction to feed the shoe past the tool.

10. A machine of the class described having, in combination, a vamp trimming tool, a blocking tool, means for actuating the trimming tool, and means for actuating the

blocking tool having provision for imparting a yielding quality to the blows of the latter tool.

In testimony whereof I have signed my 15 name to this specification in the presence of two subscribing witnesses.

ORRELL ASHTON.
